GRINDING MACHINE

Frederick J. Theler, Cincinnati, Ohio, assignor to
 Cincinnati Grinders Incorporated, Cincinnati,
 Ohio, a corporation of Ohio

Application September 25, 1931, Serial No. 565,112

22 Claims. (Cl. 51—105)

This invention relates to improvements in grinding machines and especially to improvements in a machine for grinding formed work pieces.

- 5 An object of the invention is the provision of a machine particularly adapted for rapidly grinding the sides and bottom of the shifter fork groove in transmission gears concentric with the bore thereof.
- 10 Another object of the invention is the provision of improved means for positioning the gear groove relative to the grinding wheel and for effecting the proper rotation of the gear.

15 A further object of this invention is the provision of a semi-automatic grinding machine in which the work piece is located relative to a supporting spindle and grinding wheel so that a particular portion of the work is opposite to the grinding wheel; the work piece held on the 20 spindle against accidental displacement and subsequently released and automatically ejected or stripped from the supporting spindle.

25 Other objects and advantages of the present invention should be readily apparent by reference to the accompanying drawings illustrating one embodiment of the invention and described in the following specification and it is to be understood that any modifications may be made in the exact structural details there shown and 30 described within the scope of the appended claims without departing from or exceeding the spirit of the invention.

In the drawings:

35 Figure 1 is a front elevation of a grinding machine embodying the improvements of this invention.

Figure 2 is a sectional view taken on line 2—2 of Figure 1.

40 Figure 3 is a top plan view of the parts within the grinding throat.

Figure 4 is an elevated view of the structure shown in Figure 3.

45 Figure 5 is a view illustrating certain modifications in positioning, loading and ejecting mechanisms, capable of use in performing the invention.

Figure 6 is a longitudinal sectional view through the friction driving wheel, forming a detail of the invention.

50 Figure 7 is a top plan view of the machine shown in Figure 1 and embodying an additional modification.

Figure 8 is a sectional view taken on line 8—8 of Figure 7, showing a number of the parts in 55 elevation.

Figure 9 is a sectional view taken on line 9—9 of Figure 7.

Figure 10 is a sectional view taken on line 10—10 of Figure 7.

5 Figure 11 is an end elevation of certain parts of the work support as seen from line 11—11 of Figure 7.

Figure 12 is a view of a friction connection between certain of the parts and forming a detail of the invention.

10 Throughout the several views of the drawings similar reference characters are employed to denote the same or similar parts.

15 A device of this invention may comprise a bed or support 10 having rising therefrom at one end thereof a pedestal bearing 11 rotatably supporting the spindle 12 to which is secured for movement therewith the grinding wheel 13. As shown in Figure 2 the grinding wheel is of a width substantially equal to the desired width of the groove 14 in the work or gear 15. The bed 10 is further provided in its upper surface with ways 16 for a lower slide 17 movable relative thereto toward and from the grinding wheel. A second or upper slide 18 is superimposed on the slide 17 and guided by ways formed thereon for movement relative thereto. This slide 18 carries a head 19 in which is journaled spindle 20 for the friction drive wheel 21, which effects rotation of the gear or work 15 as will later appear.

20 The gear or work 15 is provided with a splined bore receiving a similarly formed arbor 22 which has at one end a tapered shank 23 received in tapered bore 24 formed in the spindle or sleeve 25.

25 The sleeve or spindle 25 is provided on its forward end with a flange 26 through which cap screws or the like 27 extend for securing the same to a driving drum 28. Surrounding the sleeve or spindle 25 is the bushing 29 and bearing sleeve 29' whereby

30 the spindle unit is mounted for rotation in a journal 30 integral with a bracket 31 carried by the forward end of the slide 17. The driving drum 28 engages with the active surface of the friction drive or regulating wheel 21.

35 The arbor 22 is held in the spindle 25 by means of a draw bolt 32 which extends therethrough and has its head abutting an extension 33 of the spindle. The gear or work 15 is positioned or locked

40 on the arbor 22, against axial displacement, by means of a latch 34 of a width substantially equal to the width of the groove 14 into which it enters.

45 The latch 34 is pivoted at 35 intermediate its ends, and has its lower end bifurcated as at 36 receiving the reduced end 37 of the lever 38. The lever 38

50

is manually actuated about the pivot 39 which secures it to bracket 31. The latch 34 has extending from it intermediate its end an arm 40, to which one end of a spring 41 is secured. The other end of the spring 41 is secured at 42 to the bracket 31 and tends to actuate the latch 34 in a counter-clockwise direction about its pivot thereby holding the latch within the groove 14 and preventing inadvertent disassociation of the latch and gear.

As seen in Figure 1 the bed 10 carries at the end thereof a bracket 43 in which is journaled one end an adjusting screw 44. The screw 44 extends beyond the bracket 43 and carries a pilot or hand wheel. The other threaded end of screw 44 is received in a nut 46 swiveled in the rear wall of the upper slide 18. A lever 47 is secured to the swiveled nut 46 for actuating same relative to the screw 44 and advancing and retracting slides 17 and 18 as will later appear.

The friction driving or regulating wheel 21 is of the yielding type whereby the surface of the wheel will yield under undue pressure between it and the driving drum 28. This wheel may either be made of the relatively soft material, such as rubber, or, as shown in Figure 6, have an unyielding surface but so mounted as to be displaced as respects the axis of the driving spindle. As shown in Figure 6, the wheel consists of a ring 21a having secured in its bore a sleeve 48 in which is formed notches 49 receiving driving pins 50, mounted on springs 51 within suitable pockets 52 formed in the spider 53. The spider 53 in turn is keyed or otherwise secured to spindle 12.

The operation of the machine is as follows:

The lever 47 is actuated to position shown in Figure 1 which retracts the slides 17 and 18 to separate the friction driving wheel 21 from the work driving drum 28 and clear the grinding wheel 13 from the groove 14. The work locking and releasing handle 38 is actuated in a counter-clockwise direction as seen in Figure 3 to withdraw the latch 34 from the groove, whereupon the gear or work is mounted on the arbor 22 and the handle 38 released to permit the latch to again enter the groove and align the same with the grinding wheel. At this time the lever 47 is actuated in a counter-clockwise direction toward the front of the machine which effects the shifting of slide 18 along the slide 17 toward the work. This movement of the slide 18 continues until the friction drive wheel engages the driving drum 28. At this time the play between the slides 17 and 18 is taken up by the interengagement of the adjustable stop 54, carried by the arm 55 depending from the slide 18, with the rear surface of the lower slide 17. Continued movement of lever 47, therefor, effects the shifting of slides 17 and 18 as a unit relative to bed 10 to feed the work into the grinding wheel and effect a stock removal therefrom. The parts are so arranged that with the handle in a horizontal position, as compared to the vertical position, illustrated in Figure 1, the work has been ground to the desired size whereupon after a suitable dwell to permit the sparking out of the wheel and work, the reverse movement of the handle retracts the parts preparatory to introduction of a new unfinished workpiece.

The first upward movement of the handle 47 causes the slides 17 and 18 to be retracted as a unit, since any attempt to move the slide 18 will carry with it through the spring 56, secured at 57 to the lower slide and at 58 to the upper slide, 75 the lower slide 17. This unitary movement of

the slides in a rearward direction, or toward the right as seen in Figure 1, continues until the lower slide engages with an adjustable stop 59 extending upwardly from the bed 10 whereupon the lower slide is restrained from further movement permitting the retraction of the friction driving wheel from the drum 28.

The modified structure illustrated in Figure 5 consists of a slightly different loading and ejecting mechanism and comprises a bracket 60 in 10 lieu of the bracket 31, and has at one end a pair of ears 61 providing a pivotal mounting, such as 62, for the arbor 63. The arbor 63 has integral therewith and extending beyond the pivot 62, the handle 64 whereby the said arbor may be 15 oscillated about the pivot. The arbor is provided with a sleeve 65 loosely journaled thereon and terminating at one end in the drum 66 adapted to be engaged by the regulating or friction driving wheel 21. A collar 67 limits the movement of the sleeve on the arbor in one direction. The sleeve 66 has projecting from its one face driving pins 68 adapted to enter bores or holes 69 formed in the face of the work or gear 70 adjacent thereto. The gear 70 has intermediate 25 its ends the groove 71 to be ground by the grinding wheel 13. The drum 66 is positioned on the arbor to perfectly align the groove with the grinding wheel when the arbor is lowered to its operative position, which is illustrated in Figure 5. 30 In order to insure the alignment of groove with the grinding wheel the bracket 60 carries a locating pin 72 in position to enter the groove when the arbor 63 and gear 70 are lowered. The free end 73 of the arbor 63 is received between a pair 35 of upstanding lugs 74 formed at the rear end of the bracket 60.

The operation of the modified construction is as follows:

After the slides 17 and 18 have been retracted 40 to their rearmost positions the arbor 73 through the handle 64 is oscillated in a counter-clockwise direction thereby carrying the work from the grinding throat, thereupon the finished work is removed from the sleeve 65 and an unfinished 45 workpiece placed thereon. Oscillation of the arbor in a clockwise direction places the workpiece within the grinding throat so that advancement of slides 17 and 18 will effect the feeding of the work and grinding wheel as well as the rotation 50 of the work.

The modification shown in Figures 7 to 13 inclusive illustrates a semi-automatic machine for accomplishing the purpose of this invention.

As shown in Figure 8 the lever 47 has secured 55 to it a segmental gear 75 meshing with rack teeth 80 on the upper adjacent end of the rack bar 81. This rack bar 81 is provided on its opposite end with rack teeth 82 meshing with a segmental gear 83 keyed or otherwise secured to a shaft 84 which 60 extends longitudinally of the bed 10 along the rear side thereof. This shaft 84 operates mechanism for automatically retracting and inserting the locating latch as will later appear.

The lever 47 has extending from its inner face 65 and intermediate its ends a pin 85 adapted to operate in an enlarged notch 86 formed in sliding arm 87. The notch 86 forms a shoulder 88 at the upper end thereof which co-operates with the pin 85. The sliding arm 87 is guided in the bracket 89 extending upwardly from the lower slides 18 and the said arm is provided on the portion projecting below the bracket 89 with a ratchet tooth 90 co-operating with a shoulder 91 formed on plate 92, keyed or otherwise secured to the 75

rear of a shaft 93 which extends longitudinally of the machine along the forward face thereof. This shaft operates an automatic ejector mechanism which will be described in detail later.

5 The work supporting bracket illustrated in connection with this modification and particularly shown in Figures 9 and 10 is substantially the same as the bracket illustrated in Figure 2 except that it has protruding from one face thereof 0 the lugs 94 and 95 in which is slidably journaled 0 the slide rod 96 having on its forward end the grooved block 97 which receives a roller 98 carried by the free end of an arm 99 which is secured to the forward end of shaft 93 and partakes 5 of all oscillatory movement of the shaft 93 initiated by the arm 87 through the plate 92 secured to said shaft. The slide rod 96 has secured to it intermediate the lugs 94 and 95 a collar 100 which forms one abutment for a coiled spring 101 10 rounding the said slide rod 96 and which spring abuts on its other end with the lug 95.

The end of the slide rod 96 opposite to that to which the block 97 is secured carries an arm 102 which is in turn rigidly connected to the corresponding outer end of an ejector rod 103. The ejector rod 103 is journaled in a suitable bore formed through the work supporting bracket 31a which has its axis in substantial vertical alignment with the axis of the work supporting spindle. 30 The forward end of the ejector rod 103 has secured to its forward end an ejector fork 103, the arms 105 and 106 of which lie behind the rear face of the workpiece or gear 15 being slightly spaced therefrom during the grinding operation.

35 The work supporting bracket 31a has provided on its side face opposite to that on which the lugs 94 and 95 are formed with a bearing lug 107 through which is slidably a rack bar 108 having the teeth thereof meshing with rack pinion 109 on the free end of rod or shaft 84. The said pinion 109 partakes of the rotary motion imparted to the shaft 84 through the lever 47 and rack and pinion 81 and 83 for reciprocating the rack bar 108. This bar 108 carries on its free end a cam block 110 having the cam face 111 for engagement with the tail 112 of arm 113 extending from the work locator latch 34a. The cam 110 oscillates the arm 34a about its pivot against the resistance of a spring 114 tending at all times to 40 rotate the arm 34a in a counter clockwise direction or into the groove in the workpiece or gear 15.

45 The operation of the parts thus far described in connection with the modification illustrated in Figures 7 to 13 inclusive is as follows:

A workpiece 15 is mounted on spindle 22 and the lever 47 oscillated from the position shown in Figure 8 through substantially 90° in a counter clockwise direction. This movement shifts the 50 rack bar 81 to the right as seen in Figure 8 for rotating the shaft 84 clockwise and through the pinions and gears above described slides the cam rod to the left as seen in Figure 10 for permitting the spring 114 to actuate the latch 34a and cause 55 the same to enter the groove in the gear. Continued movement of the lever 47 operates the parts as above described for effecting the proper rotation of the work, stock removal therefrom and finish thereon. At the conclusion of the 60 grinding operation the lever 47 is returned to position shown in Figure 8. This movement at the beginning thereof withdraws the latch 34a from the groove and eventually picks up the arm 87 through the interengagement of the pin 85 and shoulder 88. This axial shifting of the arm 87

rotates the shaft 93 in a clockwise direction and through the arm 99 and block 97 actuates the slide rod 96 to the right as seen in Figure 9, thereby compressing the spring 101 coiled about the rod 96. Near the end of the movement of the lever 47 the arm 87 is disengaged from the plate 92 thereupon the spring 101 expands or fires carrying with it slide rod 96, arm 102, ejector shaft 103, and ejector fork 104 thereby forcefully stripping the work from the spindle 22.

5 After the unfinished workpiece has been mounted on the spindle 22 the lever is again actuated in a counter clockwise direction for properly locating the work on the spindle through the locator latch 34a and groove in work.

10 In order that the latch may be the first to come into play for properly locating the work and the first to be disengaged from the work at the conclusion of the grinding operation so as not to interfere with the automatic interjection thereof 15 the following mechanism may be employed. The pinion 109 is keyed on the hub or sleeve 115 of a member 116 which loosely surrounds the shaft or bar 84. A companion member 117 is keyed on the shaft or bar 84 and there is interposed between the members 116 and 117 a friction driving plate 118 being held under tension by means of a nut 119 on the end of the shaft 84 and clamping the parts between itself and a collar 120 secured to said shaft and lying against the adjacent face of the rack pinion 109. Adjustable stop members 121 and 122 are provided for engaging the opposite ends of the rack bar 108 for limiting its movement.

20 From the foregoing it will be noted that the shaft 84 may be rotated well beyond the amount necessary for disengaging the latch and work or gear groove but that the rack bar 108 will be shifted only the necessary distance whereupon the shaft will rotate idly due to the slippage permitted by the friction 118. From this it will also be noted that the instant the shaft 84 is reversed the actuation of rack bar 108 will likewise be reversed to the limit of its permissible movement.

25 What is claimed is:

1. In a grinding machine for grinding formed work pieces comprising a bed, a grinding wheel rotatably journaled on the bed, a slide on the bed, a work supporting bracket rotatably supporting the work, means for positioning the work on the bracket to align same relative the grinding wheel, a second slide carried by the first slide, a friction driving wheel on the second slide for effecting rotation of the work, and means for actuating the slides independently and as a unit toward and from the grinding wheel.

30 2. In a grinding machine for grinding formed pieces comprising a bed, a grinding wheel rotatably journaled on the bed, a slide on the bed, a work supporting bracket rotatably supporting the work, means for positioning the work on the bracket to align same relative the grinding wheel, a second slide carried by the first slide, a friction driving wheel on the second slide for effecting rotation of the work, and means for actuating the slides independently and as a unit toward and from the grinding wheel, said means comprising an adjusting screw, a nut carried by one of the slides having an operative engagement with the screw, and a manually actuatable lever associated with the nut for actuating same relative to the screw and for effecting a feed between the work and the wheel.

35 3. In a grinding machine for grinding the shifter fork groove in slidable transmission

- gears comprising a bed, a grinding wheel of a width substantially equal to the width of the groove to be ground, a work supporting bracket adjacent the grinding wheel, a spindle journaled in the bracket, the spindle receiving thereon the work or gear to be operated upon and including driving means for engagement with the gear, means associated with the bracket for aligning the groove in the gear with the grinding wheel, and means for rotating the spindle and work while in engagement with the grinding wheel.
4. In a grinding machine for grinding the shifter fork groove in slidable transmission gears the combination of a bed, a grinding wheel of a width substantially equal to the width of the groove to be ground, a work supporting bracket adjacent the active face of the grinding wheel, a spindle rotatably journaled in the bracket, the spindle entering the bore in the work and having complementary driving connections on the work and spindle, a latch adapted to enter the groove for aligning same with the grinding wheel and for preventing inadvertent disassociation of the work and spindle, means carried by the bracket for actuating the latch to permit replacement of the work on the spindle and means for rotating the spindle and work.
5. In a grinding machine for grinding the shifter fork groove in slidable transmission gears the combination of a bed, a grinding wheel of a width substantially equal to the width of the groove to be ground, a work supporting bracket adjacent the active face of the grinding wheel, a spindle rotatably journaled in the bracket, the spindle entering the bore in the work and having complementary driving connections on the work and spindle, a latch adapted to enter the groove for aligning same with the grinding wheel and for preventing inadvertent disassociation of the work and spindle, means carried by the bracket for actuating the latch to permit replacement of the work on the spindle and means for shifting the work toward and from the grinding wheel to effect relative feed between the work and the wheel.
6. In a grinding machine for grinding the shifter fork groove in slidable transmission gears, the combination of a grinding wheel of a width substantially equal to the width of the groove to be ground, an opposed friction driving wheel for engagement with the work for effecting and controlling its rotation, the grinding wheel and friction driving wheel being spaced from one another to form a work receiving throat therebetween, an arbor in the throat supporting the work while in simultaneous engagement with the friction driving wheel and grinding wheel, means adapted to enter the groove at a point spaced from the point of contact thereof with the grinding wheel for aligning the said groove with the grinding wheel and preventing inadvertent disassociation of the work and arbor, means establishing a driving connection between work and friction driving wheel, and means for rendering the aligning means inoperative whereby the work may be changed on the arbor.
7. In a grinding machine for grinding the shifter fork groove in slidable transmission gears the combination of a grinding wheel of a width substantially equal to the width of the groove to be ground, a work supporting bracket adjacent the grinding wheel, an arbor associated with the bracket and supporting a workpiece for rotation, means carried by the bracket for positioning the work relative to the arbor and aligning the groove with the wheel, and means for rendering the alignment means inoperative whereby the work on the arbor may be removed therefrom.
8. In a grinding machine for grinding the shifter fork groove in transmission gears the combination of a bed, a grinding wheel rotatably supported by the bed, an opposed friction drive wheel rotatably supported by the bed, the wheels being spaced from one another to form a grinding throat therebetween, a work supporting bracket within the grinding throat, a spindle rotatably journaled in the bracket, means on the spindle for frictional engagement with the friction drive wheel for rotating the work, and means for ejecting the work from the spindle at the conclusion of the grinding operation.
9. In a grinding machine for grinding the shifter fork groove in transmission gears the combination of a bed, a grinding wheel rotatably supported by the bed, an opposed friction drive wheel rotatably supported by the bed, the wheels being spaced from one another to form a grinding throat therebetween, the work supporting bracket within the grinding throat, a spindle rotatably journaled in the bracket, means on the spindle for frictional engagement with the friction drive wheel for rotating the work, means for ejecting the work from the spindle at the conclusion of the grinding operation, means for locating the work on the spindle for aligning the groove with the grinding wheel, and means for rendering the locating means inoperative.
10. In a grinding machine the combination of a bed, a grinding wheel rotatably journaled thereon, a slide supported by the bed for movement toward and from the grinding wheel, a work supporting bracket on the slide, a spindle rotatably journaled on the bracket, means for locating the work on the spindle including pivotally mounted latch, a lever for actuating the slide toward the grinding wheel to effect relative feed between the spindle and grinding wheel, and means including the lever for rendering the locating latch inoperative and for ejecting the work from the spindle.
11. In a grinding machine for grinding the shifter fork groove in slidable transmission gears comprising a bed, a grinding wheel of a width substantially equal to the width of the groove to be ground, a spindle having its axis parallel with the face of the grinding wheel and positioned adjacent thereto, the spindle receiving the work to be ground, means for locating the work relative to the spindle for aligning the groove therein with the grinding wheel and comprising a latch adapted to enter the groove at a point diametrically opposed to the point of contact with the grinding wheel, an ejector, and means for rendering the locator latch inoperative and for operating the ejector to strip the work from the spindle.
12. In a grinding machine for grinding the shifter fork groove in slidable transmission gears comprising a bed, a grinding wheel of a width substantially equal to the width of the groove to be ground, a spindle having its axis parallel with the face of the grinding wheel and positioned adjacent thereto, the spindle receiving the work to be ground, means for locating the work relative to the spindle for aligning the groove therein with the grinding wheel and comprising a latch adapted to enter the groove at a point

5 diametrically opposed to the point of contact with the grinding wheel, an ejector, means for rendering the locator latch inoperative and for operating the ejector to strip the work from the spindle, said means comprising a lever, and couplings between the lever and ejector and locating latch.

10 13. In a device of the class described for grinding the shifter fork groove in slidable transmission gears the combination of a grinding wheel, a work supporting bracket adjacent thereto and including a rotatable spindle, the spindle being adapted to enter the hole in the work or gear, means on the bracket for positioning the gear relative to the spindle and for aligning the groove therein with the grinding wheel comprising a latch pivotally mounted on the work support, yielding means for actuating the latch about this pivot and inserting same in the groove 15 at a point diametrically opposed to the point of contact with the grinding wheel, and means for rendering the latch inoperative.

20 14. In a device of the class described for grinding the shifter fork groove in slidable transmission gears the combination of a grinding wheel, a work supporting bracket adjacent thereto and including a rotatable spindle, the spindle being adapted to enter the hole in the work or gear, means on the bracket for positioning the gear relative to the spindle and for aligning the groove therein with the grinding wheel comprising a latch pivotally mounted on the work support, yielding means for actuating the latch about this pivot and inserting same in the groove at a point 25 diametrically opposed to the point of contact with the grinding wheel, means for rendering the latch inoperative, said means comprising a cam bar, a cam on the bar for engagement with the latch for actuating same about its pivot against the yielding tension of the yielding means, and means for actuating the cam bar.

30 15. In a device of the class described for grinding the shifter fork groove in slidable transmission gears the combination of a grinding wheel, a work supporting bracket adjacent thereto and including a rotatable spindle, the spindle being adapted to enter the hole in the work or gear, means on the bracket for positioning the gear relative to the spindle and for aligning the groove therein with the grinding wheel comprising a latch pivotally mounted on the work support, yielding means for actuating the latch about this pivot and inserting same in the groove at a point 35 diametrically opposed to the point of contact with the grinding wheel, means for rendering the latch inoperative, said means comprising a cam bar, a cam on the bar for engagement with the latch for actuating same about its pivot against the yielding tension of the yielding means, and means for actuating the cam bar, and additional means for stripping the work from the spindle when the locating latch is rendered inoperative.

35 16. In a grinding machine for grinding a selected portion of a work piece concentric with a previously formed portion thereon the combination of a grinding wheel, a spindle adapted to pass through a bore in the work, a bracket adjacent the operative surface of the grinding wheel, means pivotally securing the spindle to the bracket whereby upon oscillation the work is disposed in and out of alignment with the grinding wheel, and means for positioning the work relative to the spindle and grinding wheel.

40 17. In a grinding machine for grinding a

selected portion of a work piece concentric with a previously formed portion thereon the combination of a grinding wheel, a spindle adapted to pass through a bore in the work, a bracket adjacent the operative surface of the grinding wheel, means pivotally securing the spindle to the bracket whereby upon oscillation the work is disposed in and out of alignment with the grinding wheel, means for positioning the work relative to the spindle and grinding wheel, and friction 10 drive means for effecting rotation of the work relative to the grinding wheel.

15 18. In a grinding machine for grinding a selected portion of a work piece concentric with a previously formed portion thereon the combination of a grinding wheel, a spindle adapted to pass through a bore in the work, a bracket adjacent the operative surface of the grinding wheel, means pivotally securing the spindle to the bracket whereby upon oscillation the work 20 is disposed in and out of alignment with the grinding wheel, means for positioning the work relative to the spindle and grinding wheel, friction drive means for effecting rotation of the work relative to the grinding wheel, said friction 25 drive means comprising a driven member journaled on the spindle, means operatively coupling the member and work for unitary rotation, and a friction drive wheel adapted to be rotated at a relatively slow work controlling rate of speed and 30 frictionally engaging the member.

35 19. In a grinding machine of the class described the combination with a bed, of a grinding wheel rotatably mounted thereon, a work rotation and controlling slide carried by the bed for movement toward and from the grinding wheel, a work supporting bracket including a spindle on the slide for rotatably supporting the work, means for locating the work on the spindle to align a selected portion thereof with the grinding wheel, a friction drive member rotatably mounted on the slide for effecting the rotation of the work while it is supported by the spindle in contact with the grinding wheel, and manually actuatable 40 means for effecting the movement of the slide to feed the work into the grinding wheel.

45 20. In a grinding machine of the class described the combination with a bed, of a grinding wheel rotatably mounted thereon, a work rotation and controlling slide carried by the bed for movement toward and from the grinding wheel, a work supporting bracket including a spindle on the slide for rotatably supporting the work, means for locating the work on the spindle to align a selected portion thereof with the grinding wheel, a friction drive member rotatably mounted on the slide for effecting the rotation of the work while it is supported by the spindle in contact with the grinding wheel, manually actuatable means for 50 effecting the movement of the slide to feed the work into the grinding wheel, and means for rendering the locating means inoperative upon retraction of the slide and operable by the manually actuatable means.

55 21. In a grinding machine of the class described the combination with a bed, of a grinding wheel rotatably mounted thereon, a work rotation and controlling slide carried by the bed for movement toward and from the grinding wheel, a work supporting bracket including a spindle on the slide for rotatably supporting the work, means for locating the work on the spindle to align a selected portion thereof with the grinding wheel, a friction drive member rotatably mounted on 60 the slide for effecting the rotation of the work while it is supported by the spindle in contact with the grinding wheel, manually actuatable means for effecting the movement of the slide to feed the work into the grinding wheel, and means for rendering the locating means inoperative upon retraction of the slide and operable by the manually actuatable means.

65 70 75 75

- the slide for effecting the rotation of the work while it is supported by the spindle in contact with the grinding wheel, manually actuatable means for effecting the movement of the slide to feed the work into the grinding wheel, means for rendering the locating means inoperative upon retraction of the slide and operable by the manually actuatable means, and additional means for stripping the work from the spindle when it has been retracted from the grinding wheel.
22. In a grinding machine of the class described the combination with a bed, of a grinding wheel rotatably mounted thereon, a work rotation and controlling slide carried by the bed for movement toward and from the grinding wheel, a work supporting bracket including a spindle on the slide for rotatably supporting the work, means for locating the work on the spindle to align a selected portion thereof with the grinding wheel, a friction drive member rotatably mounted on the slide for effecting the rotation of the work while it is supported by the spindle in contact with the grinding wheel, manually actuatable means for effecting the movement of the slide to feed the work into the grinding wheel, means for rendering the locating means inoperative upon retraction of the slide and operable by the manually actuatable means, additional means for stripping the work from the spindle when it has been retracted from the grinding wheel, and means synchronizing the operation of the last two mentioned means whereby the work is first released from the spindle and then ejected therefrom. 5 10 15
